[57] CLAIM

The ornamental design for a video capture device, as shown and described.

DESCRIPTION

FIG. 1 is a front perspective view of a video capture device showing our new design;

FIG. 2 is a top plan view thereof;

FIG. 3 is a side elevational view thereof;

FIG. 4 is a rear view thereof; and,

FIG. 5 is a bottom plan view thereof.

The left side is a mirror image of the right side shown in FIG. 3.

The portion of a set of video cables shown in broken lines in FIGS. 1-3 are for illustrative purposes only, and form no part of the claimed design.
